UNITED STATES PATENT OFFICE.

NEWTON A. ROSE, OF WELLESLEY HILLS, MASSACHUSETTS.

HAND SHEARS.

Application filed August 1, 1924. Serial No. 729,493.

This invention relates to an improved hand shears for cutting sheet material, especially sheet metal.

It is well known that in cutting sheet metal with the ordinary hand shears, or tinsman's snippers where the two cutter levers are pivoted together, that after the first cut has been made, it is very difficult to advance the shears and make the succeeding cuts. The sheet metal tends to curl up and interfere with the forward adjustment of the hand shears necessary before a new cut can be made.

The device of this invention is easily manipulated to cut sheet metal in strips or comparatively narrow sheets, such as are used for flashing and other purposes.

To these ends the invention consists in a hand shears such as hereinafter described in the specification and particularly pointed out in the claims.

Referring to the drawings:

Figure 1 is a rear elevation of the hand shears of my invention.

Fig. 2 is an end elevation of the same as viewed from the right of Fig. 1.

Fig. 3 is a sectional elevation taken on line 3—3 of Fig. 2 and broken away to save space.

Fig. 4 is a detail sectional plan taken on line 4—4, Fig. 2.

Fig. 5 is a sectional elevation taken on line 5—5, Fig. 1.

Like numerals refer to like parts throughout the several views of the drawings.

In the drawings, 5 is a frame comprising an elongated base 6. 7 is a cylindrical portion and 8 is a standard which connects the front ends of the base 6 and 7 together. A cutter blade 9 is fastened to the front end of the base 6, and extends transversely thereof, said base being provided with a slot 10 extending longitudinally thereof from the front end of the base adjacent to the upper edge of said cutter blade 9, and terminating adjacent the rear end of said base 6. A cutter blade slide 11 is mounted to be reciprocated in ways 12 provided in the front of the standard 8 and has fastened thereto a cutter blade 13 adjacent to the cutter blade 9 and adapted to co-act therewith to sever sheet material inserted between the edges of the cutter blades 9 and 13, and projecting into the slot 10.

A reciprocatory motion is imparted to the slide 11 by a handle lever 14 which is pivot-

ed to a stud 15 on a bracket 16. The pivotal stud 15 consists of two cylindrical portions 24, an intermediate portion 25 eccentric to the cylindrical portions 24, a head 26 and a screw-threaded portion 27 concentric with the cylindrical portions 24. The head 26 is provided with a screw driver slot 26' and with oppositely disposed notches 28 and 29 in its periphery. A nut 30 has screw-threaded engagement with the screw-threaded portion 27 of the stud 15 and a locking pin 31 is inserted in the bracket 16. By removing the pin 31 and by rotating the stud 180° by means of the head 26, the notch 29 may be brought into position to have the pin 31 inserted therein, thus the pivot, or intermediate portion 25 of the stud 15 may be rotated and locked in position to bring it toward or away from the slide 11, and thus respectively increase or diminish the leverage of the lever 14. The bracket 16 is adjustably fastened to the standard 8 by screws 17 which project through slots 18 provided in the bracket 16 and have screw-threaded engagement with the standard 8. The front end of the lever 14 is provided with a slot 14' through which a pin 11' rigidly fastened to the slide 11 projects. It will thus be seen that in effect the lever 14 is pivoted to the standard 8 and that the pin 11' forms a part of the slide 11 so that the slide 11 may be moved by the lever 14 engaging the same. The lever 14 is positioned in the space between the handle 7 and the base 6. A stop screw 19 has screw-threaded engagement with a bracket 20 which is rigidly fastened to the frame 6 at the upper end of the standard 8. The upper end of the cutter slide 11 abuts against the screw 19 when it is moved to its uppermost position by a spring 21 interposed between the handle 7 and the handle 14.

An arm 22 on the standard 8 projects longitudinally of the cutter blades 9 and 13 adjacent to the cutter blade 13 and with its lower face approximately flush with the upper side of the slot 10, said arm constituting a stripper and operating to prevent the sheet metal from moving upwardly or curling when the cutter blade is moved upwardly.

The object of the stop screw 19 is to compensate for any change in the relative position of the cutting edge of the cutter 13 relatively to the cutting edge of the cutter blade 9 caused by the grinding and sharpen-

ing of said cutter blades, it being evident that the cutting edges of the two cutters may always be located in the same relative positions when the cutter blade 13 is in its uppermost position by adjusting the stop screw 19.

It will be seen that by adjusting the slide 11 and its cutter blade 13 to the position illustrated in Fig. 2 the shears cannot be advanced to a sufficient extent when a new cut is about to be made to allow the portion of the metal which has not been severed to project beyond the rear ends of the cutter blades, or the right-hand ends of the cutter blades as viewed in Fig. 2, thus the cut made by the shears will be continuous and the two parts of the metal being cut will be entirely severed from each other. The bracket 16 being made adjustable on the standard 8, renders it possible to always position the pivot 15 so that the handle 14, when in its lowermost position will occupy the position illustrated in Fig. 1, otherwise if the cutter slide 11 should be adjusted downwardly by means of the adjustable stop screw 19 to compensate for the material which has been ground off the cutting edges of the cutter blades 13 and 9 the lever 14 will gradually be moved upwardly at its rear end and thus prevent said lever from being moved toward the handle 7 during the cutting operation to a sufficient extent to cause the cutter blades to make a full length cut.

The general operation of the shears is as follows:—Assuming the parts to be in the relative positions illustrated in Fig. 2, a piece of sheet metal 23 shown in section in Fig. 2 is inserted between the cutting edges of the cutter blades 9 and 13 and projects into the slot 10 to an extent equal to the width of the strip which it is desired to cut from the main piece of sheet metal. The user of the tool grips the handles 14 and 7 with one hand and causes the handle lever 14 to move toward the handle portion 7 of the frame. The handle lever 14 thus being tipped upon its pivot 15 causes the cutter slide 11 and its cutter blade 13 to move downwardly and the cutter blade 13 co-acting with the cutter blade 9 causes the sheet metal 23 to be severed for a length approximately equal to the cutting edges of said cutter blades 13 and 9. Upon releasing the pressure upon the lever 14, the same will be carried back to the position illustrated in Fig. 1 by the spring 21, thus causing the cutter blade slide and its cutter blade 13 to move upwardly until the upper end of the cutter slide 11 abuts against the lower end of the stop screw 19.

The tool is now moved longitudinally of the cut which has been made, that is, longitudinally of the cutter blades 9 and 13, until the forward end of the cut which has just been made is brought approximately to the

rear ends of the blades 9 and 13, or the right hand ends of said blades as viewed in Fig. 2 and the operation just described is again repeated.

This operation is continued until one piece of the metal has been severed from the remainder. During these successive cutting operations it will be seen that when the cutter blade 13 is moved upwardly, the metal, being severed, cannot follow it on account of the stripper arm 22 which bears against that portion of the metal which is being severed from the main piece of metal.

I claim:

1. A hand shears having, in combination, 80 a frame comprising an elongated base, a handle portion spaced apart therefrom, and a standard connecting the front ends of said base and handle portion, a cutter blade fast to the front end of said base and extending transversely thereof, said base being provided with a slot extending longitudinally thereof from its front end adjacent the upper edge of said cutter blade, a cutter slide 85 slidably mounted in the front of said standard, and embodying therein a cutter blade adjacent said first-named cutter blade, a bracket adjustably mounted on said standard and a lever pivoted to said bracket and adapted to engage said cutter blade slide 90 whereby a reciprocatory motion may be imparted to said slide and its cutter blade to sever a piece of sheet material inserted between said cutter blades and projecting into 100 said slot.

2. A hand shears having, in combination, a frame comprising an elongated base, a handle portion spaced apart therefrom, and a standard connecting the front ends of said base and handle portion, a cutter blade fast 105 to the front end of said base and extending transversely thereof, said base being provided with a slot extending longitudinally thereof from its front end adjacent the upper edge of said cutter blade, a cutter slide 110 slidably mounted in the front of said standard, and embodying therein a cutter blade adjacent said first-named cutter blade, a lever pivotally mounted on said standard and positioned between said handle and said base, and engaging said cutter blade slide, a spring inserted between said lever and handle and a stop screw on said frame against which said cutter blade slide is adapted to abut when moving upwardly, whereby a piece of sheet material inserted between said cutter blades and projecting into said slot 115 may be severed by said cutter blades.

3. A hand shears having, in combination, 125 a frame comprising an elongated base, a handle portion spaced apart therefrom, and a standard connecting the front ends of said base and handle portion, a cutter blade fast to the front end of said base and extending transversely thereof, said base being pro- 130

vided with a slot extending longitudinally thereof from its front end adjacent the upper edge of said cutter blade, a cutter blade holder slide slidably mounted in the front of 5 said standard, a cutter blade fast to said slide adjacent said first-named cutter blade, means to reciprocate said slide and a stripper arm on said base positioned adjacent to 10 said movable cutter blade and projecting longitudinally thereof adjacent to the upper side of said slot, whereby a piece of sheet material inserted between said cutter blades and projecting into said slot may be severed by said cutter blades.

15 4. A hand shears having, in combination, a frame comprising an elongated base, a handle portion spaced apart therefrom, and a standard connecting the front ends of said base and handle portion, a cutter blade fast 20 to the front end of said base and extending transversely thereof, said base being provided with a slot extending longitudinally thereof from its front end adjacent the upper edge of said cutter blade, a cutter blade 25 slide slidably mounted in the front of said standard, a cutter blade fast to said slide adjacent said first-named cutter blade, a pivot mounted on said standard and adjustable toward and away from said slide, and a lever 30 mounted on said pivot and positioned between said handle and said base, and engaging said cutter blade slide whereby a reciprocatory motion may be imparted to said slide and its cutter blade to sever a piece of 35 sheet material inserted between said cutter blades and projecting into said slot.

5. A hand shears having, in combination, a frame comprising an elongated base, a handle portion spaced apart therefrom, and a 40 standard connecting the front ends of said base and handle portion, a cutter blade fast to the front end of said base and extending

transversely thereof, said base being provided with a slot extending longitudinally thereof from its front end adjacent the upper edge of said cutter blade, a cutter blade slide slidably mounted in the front of said standard, a cutter blade fast to said slide adjacent said first-named cutter blade, an eccentric stud constituting a pivot mounted 45 on said standard, and a lever mounted on said pivot and positioned between said handle and said base, and engaging said cutter blade slide whereby a reciprocatory motion may be imparted to said slide and its cutter 50 blade to sever a piece of sheet material inserted between said cutter blades and projecting into said slot.

6. A hand shears having, in combination, a frame comprising an elongated base, a handle portion spaced apart therefrom, and a standard connecting the front ends of said base and handle portion, a cutter blade fast to the front end of said base and extending transversely thereof, said base being provided with a slot extending longitudinally thereof from its front end adjacent the upper edge of said cutter blade, a cutter blade slide slidably mounted in the front of said standard, a cutter blade fast to said slide adjacent 60 said first-named cutter blade, a pivot mounted on said standard and adjustable in different directions thereon, and a lever mounted upon said pivot and positioned between said handle and said base, and engaging 65 said cutter blade slide whereby a reciprocatory motion may be imparted to said slide and its cutter blade to sever a piece of sheet material inserted between said cutter blades and projecting into said slot.

70 In testimony whereof I have hereunto set my hand.

NEWTON A. ROSE.
